AU 292

EX

OR D 10,241

No. 10,241

Sept. 11- 1877.

UNITED STATES PATENT OFFICE.

ALFRED J. MANNING, OF NEW YORK, N. Y., ASSIGNOR TO ANDREW DOUGHERTY, OF SAME PLACE.

DESIGN FOR BACKS OF PLAYING-CARDS.

Specification forming part of Design No. **16,241**, dated September 11, 1877; application filed August 4, 1877.
[Term of Patent 7 years.]

To all whom it may concern:

Be it known that I, ALFRED J. MANNING, of the city, county, and State of New York, have invented and produced a new Design for Backs of Playing-Cards, of which the following is the specification:

The main feature of the design is an ivy-vine, which is so disposed that the stem forms an oval panel, A, in the center and circles C C in the corners.

Within the oval A is a diamond-shaped panel, B, having a dotted border containing a central star and ivy-leaves arranged radially around it.

I claim—

1. The design for the back of a playing-card, consisting of an ivy-vine, substantially as shown and described.

2. The design for the back of a playing-card, consisting of the ivy-vine arranged to

form an oval, A, and circles C C, as described and shown.

3. The design for the back of a playing-card, consisting of the diamond-shaped panel B, its central star, and ivy-leaves, substantially as shown and described.

4. The design for the back of a playing-card, consisting of the diamond-panel B, having a dotted border arranged in curved lines to form a diamond, substantially as shown and described.

In testimony whereof I have signed my name to this specification in the presence of two subscribing witnesses.

ALFRED J. MANNING.
